UNITED STATES PATENT OFFICE.

FRANK S. WEYRS, OF PHILADELPHIA, PENNSYLVANIA.

AUTOMATIC ADJUSTABLE HOLDER FOR TELEPHONE INSTRUMENTS.

980,465.

Specification of Letters Patent. Patented Jan. 3, 1911.

Application filed April 19, 1909. Serial No. 490,218.

To all whom it may concern:

Be it known that I, FRANK S. WEYRS, a citizen of the United States, residing at Philadelphia, in the county of Philadelphia and State of Pennsylvania, have invented a certain new and useful Improvement in Automatic Adjustable Holders for Telephone Instruments, of which the following is a specification.

10 My invention relates to a new and useful improvement in automatic adjustable holders for telephone instruments, and has for its object to enable the user of phones to not only free himself of an obnoxious way 15 of clutching the receiver when telephone is used, more so saving considerable time and anxiety.

By the use of my automatic adjustable attachment a combination of ways to automatically actuate the switch in or off use, means are provided for holding the receiver supporter in certain desired positions or to have the instrument locked.

With these ends in view, this invention 25 consists in the details of construction and combination of elements hereinafter set forth and then specifically designated by the claims.

In order that those skilled in the art to 30 which this invention appertains may understand how to make and use the same, I will describe its construction in detail, referring by letter to the accompanying drawing forming a part of this specification, in 35 which—

Figure 1 is an elevation of a telephone instrument showing my improvement applied thereto, portions being in section to more clearly illustrate its construction. Fig. 2, a 40 side view of a portion of the sustaining post partly broken away. Fig. 2^B, an elevation of the receiver supporting device. Fig. 3, a perspective view showing a slightly modified form of my improvement in which pivoted arms are utilized for supporting the 45 telephone instrument and actuating automatically upon the switch hook in unison with the telephone bracket. Fig. 4, a detail view of the sliding block and the lower half 50 of the yoke in which the receiver is clamped. Fig. 5, an elevation of a slightly modified form of the construction shown in Fig. 3 in which the switch hook is omitted in the tele-

phone instrument and the switch which was usually operated by said hook operated instead by a central pin and bell crank lever. Figs. 6, 7, 8 and 9, detail views of the swivel joint between the supporting means and the cross rods upon which the transmitter is supported. Fig. 10, a section of a portion of the supporting means showing a friction spring located therein for holding such suitable means in any adjustment within its socket, and Fig. 11, a plan view of the base plate upon which the telephone instrument and attachment thereto shown in Fig. 5 is supported, and the mechanism carried by said plate.

In carrying out my invention as shewn in Figs. 1 and 2. A represents the base plate, upon which the base B of the telephone instrument is placed and secured by the hook clutches m, and projecting upward from this base plate is a sustaining post C. Upon the top of this sustaining post is a stud D, on which is pivoted the cylindrical block E, which latter has a groove F formed therein of such shape as to actuate the shoe G up or down as the case might be. When the telephone is not in use the shoe G rests at the base of an incline to block E. To open communication, arm N Fig. 2^B is caused by a slight pull to be brought forward, when shoe G begins to move up the incline to groove F, to a point on the extreme right for the use of both the right or left ear. Reversed action is caused to be instituted by a slight pressure upon key, again closing communication. H is a bracket projecting from the sustaining base and this bracket has pivoted to its upper end the lever I, to which lever is pivoted the rod J, the latter being adjustably set in the bar K and held in any adjustment therein by the set screw L. The bar K is fitted to slide in the bracket H and has attached thereto the shoe G so that when the block E is revolved the bar K and rod J will be moved up or down imparting a corresponding movement to the lever I; this lever actuating upon the switch hook M it follows that the revolving of the grooved block will open or close the switch in the same manner as is usually the case when the ordinary receiver is taken off or put on the hook.

In Fig. 2^B, N is an arm projecting from

the grooved block E, and to the outer end of this arm is pivoted the tubular socket O by the set joint P which permits the adjustment of the socket at various angles to said arm. 5 O' is a supporting tube or rod which is adapted to slide in the socket and has set therein a friction spring Q of sufficient spring to hold the tube O' in its various heights of adjustment within the socket, and 10 this construction will permit of this tube being raised or lowered or swung upon its axis, Fig. 2, as occasion may require. On the outer end of the tube O' is supported the swivel joint consisting of the head R, cap 15 R', the former having a cone shaped lug R² over which fits a corresponding recess formed in the cap R'. A suitable screw R² passes through the cap and is threaded into the head so as to hold these two members in 20 position relative to each other. S is one or more rods which pass through the holes S' formed in the cap and upon these rods the block T is fitted to slide, said block having swiveled thereto the yoke T', upon the stud 25 T². This yoke is made in two sections in order that the ordinary telephone receiver may be clamped therein, or as shown in Fig. 5, a watch case receiver may be substituted for the yoke. Within the sustaining post is 30 fitted a spring actuated locking bolt U, the nose of which is adapted to engage with the ratchet teeth, holes or projections U' formed upon the bottom of the grooved block E, thus holding this block against reverse rotation by the action of the spring V, which latter is coiled around the stud D, one end being connected with the block E, while the other end is attached to the cap V', which is held upon the stud by the set screw V². 35 The tension of this spring may be increased or decreased by the revolving of the cap V', after which the cap is again secured upon the stud by the set screw V². From this it will be seen that when the arm N, Fig. 2^b, 40 carrying the parts which support the receiver is swung forward in position to be used, the switch hook M will be permitted to swing upward by the action of the groove F, upon the shoe G, as before described, and the 45 arm N, Fig. 2^b, will be held in this position by the nose of the lock U engaging with the ratchet teeth, hole or projection U', but after the telephone has been used and it is desired to return the receiver to its normal position 50 it is only necessary to depress the lock U out of engagement with the ratchet teeth, hole or projections, when the spring V will cause to swing the grooved block and the parts attached thereto back to their normal 55 position and this is accomplished by the key W being turned so that the tang thereof which bears upon a pin carried by the bolt will depress the bolt against the action of its 60 spring. 65 In order that the instrument may be

locked so that it cannot be used by unauthorized persons, I provide a forked lever a so that the tang of the key will pass into the forked portion of said lever to throw the pin b into engagement with a corresponding hole in the bottom of the grooved block, thus locking said block so that the arm N cannot be swung forward, thus holding the switch hook down, but when the key is turned in the opposite direction it will withdraw this pin and consequently permit the swinging of the arm. 70

In Fig. 3 the socket O² has fitted therein the supporting rod O², upon the upper end of which is secured the head R, which is the same as that described in connection with Fig. 1. This socket is pivoted upon the upper end of the sustaining post C' formed with the base plate A' and the stud A² is pivoted or swiveled in the end of the bar A³. A' is a guide socket through which the rod 1 passes, the upper end of this rod being bent and having a loop or eye 2 formed thereon adapted to embrace the post of the telephone apparatus about the switch hook M, in order that when this rod is moved up or down it will actuate said hook. 10 is a lever pivoted at 11 to a telephone bracket arm, which for convenience sake we will number 3, 4, 5, 6, 7, 8, 9 and 14, and pivoted to 5 connected by a link 12, to the lower end of the rod 1, and this lever is also attached to the arm 6 by the hook 13. Thus when the telephone instrument is drawn downward, as for use, the peculiarity difference in distance apart of the levers 5 and 6 will cause the lever 10 to press the rod 1 upward thus permitting the upward movement of the switch hook to close the circuit, while upon the reverse movement of the instrument the rod 1 will draw the switch hook downward. The actuating of arms 5 and 6 will reverse while link 12 comes in action in pulling down rod 1, whereas hook 13 permits a free movement of rod 10. Should it be desired to operate the switch hook independent of the movement of the instrument this may be accomplished by depressing the outer end of the lever 10, which is permitted by its loose connection with the arm 6 through the hook 13. 100

In Fig. 5 a slight modification of the construction just described is shown, in which the switch hook is omitted in the telephone instrument, and the long member 15 of the ordinary switch is connected with a slide bar 16, the latter being actuated by the bell crank lever 17, which is operated by the central pin 18, the lower end of which rests upon the lever 10. This arrangement will operate the switch member 15 when the instrument is moved up or down in the same manner as above described in connection with the construction shown in Fig. 3. The post O³ in this construction has set therein 110

120

125

130

a spring 19 which is so bent as to bring one or more of its angles in contact with the inner surface of the socket 17.

Having thus fully described my invention, what I claim as new and useful, is—

1. In combination with a telephone instrument, a base plate to which the base of said telephone instrument is secured, a sustaining post projecting upward from the base plate, a grooved block fitted to revolve upon said post, means dependent upon the revolving of said block for actuating the switch hook, an arm projecting from the block, a socket pivoted to the arm, a means adapted to slide through the socket, a swivel joint carried by the upper end of the tube, one or more rods fitted in one of the members of said joint, a sliding block fitted upon the rods, and a yoke swiveled upon the last named block for supporting the telephone receiver, as specified.
2. In combination with a telephone instrument, a base plate for supporting said instrument, a sustaining post projecting upward from the base plate, a grooved block pivoted upon said post, means connected with the block for supporting the telephone receiver, and means dependent upon the rotation of the block for acting upon the switch hook to open and close the hook switch, as specified.
3. In combination with a telephone instrument, a base plate for supporting said instrument, a sustaining post projecting up-

ward from the base plate, a grooved block pivoted upon said post, means connected with the block for supporting the telephone receiver, means dependent upon the rotation of the block for actuating the switch hook, a spring for holding the grooved block in its normal position, a lock for holding the grooved block against the action of its spring, and means for releasing the block to permit it to return to its normal position, as specified.

4. The herein described combination of a base plate for supporting a telephone instrument, a supporting post projecting upward from the base plate, a block adapted to revolve upon said post, said block having a groove formed therein, a lever adapted to depress the switch hook of the telephone, a rod pivoted to said lever, a tube in which said rod is adjustably secured, a shoe carried by the tube and traveling in the groove in the block, an incline, a spring for holding the block in its normal position, ratchet teeth formed upon the bottom of the block, locking mechanism adapted to engage said teeth, and means supported by the block for carrying the telephone receiver, as specified.

In testimony whereof, I have hereunto affixed my signature in the presence of two subscribing witnesses.

FRANK S. WEYRS.
